United States Patent Office.

JAMES ALCORN, OF CHARLESTOWN, MASSACHUSETTS, ASSIGNOR TO JAMES N. MELVIN FOR ONE-THIRD, AND THOMAS QUINN FOR ONE-THIRD, OF SAME PLACE.

Letters Patent No. 90,979, dated June 8, 1869.

IMPROVED CLOTHES-RACK.

The Schedule referred to in these Letters Patent and making part of the same.

To all whom it may concern:

Be it known that I, JAMES ALCORN, of Charlestown, in the county of Middlesex, and State of Massachusetts, have invented a new and improved Clothes-Rack; and I do hereby declare that the following is a full, clear, and exact description thereof, which will enable others skilled in the art to make and use the same, reference being had to the accompanying drawing, forming part of this specification.

The object of this invention is to provide a simple and efficient folding clothes-rack, which may be readily adjusted to suspend the hinged holding-bars horizontally for holding the clothes, or vertically to hang in the most compact position, and without strain on the suspending parts, all as hereinafter more fully specified.

Figure 1 represents a side elevation of my improved clothes-rack and sectional view of the holding-bracket.

Figure 2 represents a front elevation with parts removed.

Similar letters of reference indicate corresponding parts.

A represents a metallic yoke, wherein a series of clothes-bar B is pivoted by a spindle, C, passing through holes in the ears D of the said yoke.

This yoke is pivoted, by a bolt, E, to a bracket, F, adapted for ready attachment by screws or otherwise to the side wall of a house, post, or other like place.

It is desirable to turn these bars B, when not required for use, so that they will hang downward from

the spindle C, whereby they are less exposed to be broken or to swing back and forth in the wind.

For this purpose I arrange the yoke so as to swing to some extent on the pivot E, and I form an enlarged disk around the axial hole, having a handle, G, projecting from one side, and a pin, I, projecting into a curved slot in a disk, K, fixed to the bracket F.

When the rack is to be used, the handle G is turned into the position represented in fig. 2, and secured by a pin, L, which holds the yoke and spindle in vertical position, and consequently the arms B in a horizontal position, as represented in the drawings.

The two pins H and L prevent the rack from being moved either way by the wind while supporting the clothes.

When the rack is not to be used, the pin L is taken out, and the yoke allowed to swing around into a horizontal plane, to permit the arms to hang therefrom.

Having thus described my invention,

What I claim as new, and desire to secure by Letters Patent, is—

The combination of the yoke A supporting the arms B, with the bracket L when pivoted thereto, and arranged for adjustment substantially as specified.

JAMES ALCORN.
